UNITED STATES PATENT OFFICE.

WILLIAM S. PIERCE, OF FRANKLIN, PENNSYLVANIA, ASSIGNOR OF ONE-HALF TO
CHARLES A. PIERCE, OF FRANKLIN, PENNSYLVANIA.

WELL-PACKER.

1,091,386.

Specification of Letters Patent.

Patented Mar. 24, 1914.

Application filed April 11, 1913. Serial No. 760,526.

To all whom it may concern:

Be it known that I, WILLIAM S. PIERCE, a citizen of the United States, residing at Franklin, in the county of Venango and State of Pennsylvania, have invented certain new and useful Improvements in Well-Packers; and I do hereby declare the following to be a full, clear, and exact description of the invention, such as will enable others skilled in the art to which it appertains to make and use the same.

My invention relates to improvements in well packers, and consists in the constructions, combinations and arrangements herein described and claimed.

The object of my invention is to provide an improved well packer adapted to be readily set in position and to efficiently pack a well under all practical conditions, and which can be readily released and pulled after having been set.

In the accompanying drawings forming a part of this application, and in which similar reference symbols indicate corresponding parts in the several views:—Figure 1 is a vertical axial section, illustrating one embodiment of my invention, with the parts in position for insertion in a well; Fig. 2 is a side elevation, showing the parts in the position assumed when pulling the packer, the lower casing section being partly broken away; Fig. 3 is a bottom plan view of the construction shown in Fig. 1, and Fig. 4 is an enlarged detailed section on the line 4—4 of Fig. 3.

Referring especially to Figs. 1-4 of the drawings, 1 indicates a tubular casing section slidably fitting within a hollow section 2 and having a coupling 3 threaded in its upper end for attachment to the usual well tubing. The casing section 1 carries a peripheral packing sleeve 4 of rubber, or other suitable material, adapted to be expanded by the section 2 when said casing sections are forced together.

The section 2 is provided with a threaded lower end 5 adapted to engage the well tubing for firmly supporting said section in position within a well. An upwardly extending pipe 6 is screwed in the threaded portion 5 of said section 2 and provided with heads 7 and 8 and a suitable packing, such as a leather cup 9 telescoping within the tubular section 1; a flange 10 being formed on said section 1 for engaging said head 7

to limit the separation of said sections 1 and 2, as shown in Fig. 2.

A threaded key 11 is driven in, or otherwise detachably secured to, the section 2 and carries a mutilated nut 12 adapted to engage a slot in a tube 13 secured to the section 1 and extending slidably through said section 2; thereby providing means for detachably locking said casing sections 1 and 2 together in position for ready insertion in a well, as shown in Fig. 1.

In the operation of this improved construction, the casing sections are secured together by the nut 12 in the position shown in Fig. 1, and then lowered in the well until the lower end of the section 2 engages and is supported by the well tubing. Pressure is then applied to the line of well tubing extending upwardly from the coupling 3 of the upper section 1 to drive said section 75 within the hollow section 2, and thereby set the packing by expanding the packing sleeve 4 into tight engagement with the walls of the well for efficiently preventing the escape of gas or liquid there past. During such downward forcing of the casing section 1, the tube 13 forces the key 11 from the section 2 and said key drops to the bottom of the well. If desired, the casing section 1 can be forced downward within the section 2 85 by dropping a line of small piping on said section 1. After the packer has been thus set, it can be readily released and pulled out by raising the well tubing secured to the upper threaded coupling 3. In this operation, the tubular casing section 1 will be withdrawn from the section 2 and raised thereabove until the flange 10 of said section 1 engages the head 7 on the pipe 6 of said section 2; thereby withdrawing the section 1 from the packing sleeve 4 and permitting said sleeve to contract from its expanded position. The parts will be then in their relative positions shown in Fig. 2 and the packer can be readily pulled from the well by elevating the well tubing secured to the upper coupling 3 of said packer.

I have illustrated and described preferred and satisfactory constructions, but changes could be made within the spirit and scope 105 of my invention.

I claim:—

1. In a well packing, the combination of a casing comprising two relatively movable sections; an expandable packing carried by 110

2

said casing; a member secured on one of said sections; a member detachably mounted on the other section and adapted to engage with said secured member for holding the sections in spaced relation when lowering into position, and to allow said sections to separate for removal from the well; a pipe section carried by one of said casing sections and constructed with a head; and a flange formed on the other casing surrounding said pipe and adapted to engage with said head whereby to remove the casing sections from the well.

10 2. In a well packing, the combination of

a casing comprising two relatively movable sections, a tube secured to one of said sections and slidably telescoping in the other of said sections, a packing for said telescoping portion of the tube, an expandible packing sleeve carried by said casing, and means for moving one of said members relative to the other for expanding said packing sleeve.

In testimony whereof, I affix my signature, in presence of two witnesses.

WILLIAM S. PIERCE.
